CLAIM

The ornamental design for a medical device electronic connector cable as shown and described.

DESCRIPTION

FIG. 1 is a front elevation view of a medical device electronic connector cable.

FIG. 2 is a rear elevation view thereof.

FIG. 3 is a top plan view thereof.

FIG. 4 is a bottom plan view thereof.

FIG. 5 is a left side view thereof.

FIG. 6 is a right side view thereof.

FIG. 7 is a first perspective view thereof; and,

FIG. 8 is a second perspective view thereof.

In the drawings, the broken lines are for the purpose of illustrating portions of the medical device electronic connector socket that form no part of the claimed design.
